DUNCAN W. SHANNON AND THADDEUS N. HARRIS, OF KEY WEST, FLORIDA.

SPARK-PLUG.

1,293,218.

Specification of Letters Patent.

Patented Feb. 4, 1919.

Application filed February 6, 1918. Serial No. 215,653.

To all whom it may concern:

Be it known that we, DUNCAN W. SHANNON and THADDEUS N. HARRIS, both citizens of the United States, residing at Key West, 5 in the county of Monroe and State of Florida, have invented certain new and useful Improvements in Spark-Plugs, of which the following is a specification.

This invention relates to spark plugs specially adapted for use in connection with internal combustion engines.

One of the main objects of the invention is to provide a spark plug of simple construction and operation which may be 15 readily applied to an internal combustion engine of standard construction. A further object is to provide a plug the various parts of which may be quickly and easily disassembled for cleaning or repairing. A 20 further object is to provide a spark plug provided with means for securing the terminal carrying elements in proper position and for also closing the casing which carries the plug when the plug is removed thus permitting 25 the plug to be removed without stopping the engine. Further objects will appear from the detailed description.

In the drawings:

Figure 1 is a longitudinal section through 30 a plug constructed in accordance with our invention.

Fig. 2 is a top plan view of the plug.

Fig. 3 is a longitudinal section through 35 the plug showing the terminal carrying members in partial withdrawn position.

The body or casing 1 of the plug is of usual construction being provided intermediate its ends with an integral nut 2 and having the tapered threaded neck 3 which 40 is adapted to be threaded into the usual bore 4 provided in the cylinder head 5. The casing 1 receives a cylindrical metallic sleeve 6 threaded therein. This sleeve is provided at its outer end with a hexagonal head 7 45 which facilitates threading of the sleeve into and out of the casing. Head 7 is provided with a central cylindrical recess which receives the threaded neck 8 of a securing nut 9. A tube 10 of porcelain or other suitable 50 insulating material is mounted in tube 6 and is provided, at its inner end, with a tapered portion 11. This tube is provided with a terminal member 12 in the form of a metallic rod which extends the full length 55 of the tube, the inner end of this rod being spaced over the arcuate terminal member 13

carried by the tube 6 at the inner end thereof. The tube 6 is provided at its inner end with an inner annular shoulder 14 which engages the shoulder at the inner end of tube 60 10 formed by the reduced portion 11. This shoulder acts to positively limit the inward movement of the tube. The outer portion 11^a of tube 10 is slightly tapered, and the securing nut 9 is provided with a corresponding 65 axial bore. By threading nut 9 into head 7 the insulating tube 10 is forced inwardly and secured in proper position so as to have the terminal members disposed in proper spaced relation. A metallic disk 15 is secured 70 on the outer end of tube 10 and carries an outer copper contact disk 16. A binding nut 17 is threaded on the outer end of rod 12 and acts to secure one end of a wire in close engagement with disk 16 in the well known 75 manner.

The casing or body 1 is provided with a diametrical bore 18 which is adapted to receive a locking and closing screw 19 threaded therein. When the plug is in use, the inner end of this screw engages into an annular groove 20 formed in the outer face of sleeve 6. In this manner screw 9 effectually prevents rotation of the sleeve thus securing the contact points in proper relation to each 85 other.

In use this spark plug will operate in the well known manner, the terminal rod 12 being connected to one side of the battery through the usual induction coil, and the engine being grounded to the other side of the battery. If the plug needs to be cleaned or repaired while the engine is in operation, this may be effected without stopping the engine. By turning the screw 19 out of engagement with the tube 6, the tube and the elements carried thereby may be readily removed from the body or casing 1. When the sleeve has been turned outwardly a sufficient distance to insure that the inner terminal 95 member 18 is beyond the screw 19, screw 19 is then turned in so as to extend completely across the bore of body 1 thus effectually closing the same, it being understood, of course, that the diameter of the screw is 100 slightly greater than the interior diameter of casing 1. After the screw has thus been turned in so as to close the casing, the sleeve 6 and the parts carried thereby may be completely removed thus permitting the plug to 105 be quickly and easily cleaned or repaired. During the repairing or cleaning of the 110

plug, it is not necessary to stop the engine as the casing 1 is closed, as above noted. When the plug has been repaired it may be threaded into the casing 1 a short distance, 5 after which the screw 19 is turned out so as to clear the sleeve, the tube then being threaded inward into its innermost position. To prevent damage or bending of the articulate terminal element 13 due to contact with 10 the screw 19, the sleeve 6 may be provided, a proper distance from its inner end, with an annular mark or groove 21 so positioned, that, when the tube has been turned a sufficient distance outward in casing 1 to render 15 this groove visible the inner end of member 13 will be positioned beyond the bore 18.

What we claim is:

1. In spark plugs, a casing, a tube mounted in said casing, means for releasably securing said tube in the casing, said securing means being adapted to close the casing when the tube is removed therefrom.
2. In spark plugs, a casing having a longitudinal threaded bore and a transverse threaded bore intersecting the same, a sleeve threaded into said longitudinal bore and containing an insulating element, the sleeve and element carrying the terminals, and a screw threaded into said transverse bore against the sleeve, the screw being of a size 25 to be projected across the longitudinal bore when the sleeve is withdrawn and close said bore at that time.
3. In a spark plug, the combination with 30 a casing having a longitudinal threaded bore and a diametric threaded bore intersecting the same, said bores being of approximately the same size; of a sleeve threaded into said

longitudinal bore and having an external annular groove adapted to register with said 40 diametric bore when the sleeve is in proper position, an insulating element carried within the sleeve, terminals carried by the sleeve and element, and a screw threaded into said diametric bore and engaging said 45 groove when the sleeve is in place or adapted to be projected across its longitudinal bore to close the same when the sleeve is withdrawn.

4. In spark plugs, a casing having a longitudinal bore, a tube threaded through said casing, the casing being also provided with a diametrical bore, and a screw threaded into said diametrical bore for engagement with the tube so as to normally prevent rotation thereof, said screw being adapted to extend across the interior of said casing so as to completely close the same when the tube is removed.

5. In spark plugs, a casing, a tube mounted in said casing and provided at its inner end with a terminal member, means for releasably securing said tube in the casing, and a terminal member carried by the tube and electrically insulated therefrom, said terminal member being spaced from the first mentioned terminal member, and said securing means being adapted to close the casing when the tube is removed therefrom.

In testimony whereof we affix our signatures in presence of two witnesses.

DUNCAN W. SHANNON.
THADDEUS N. HARRIS.
